UNITED STATES PATENT OFFICE.

JOHN C. FLYNN, OF NEW YORK, N. Y.

DESIGN FOR A CABINET-DESK.

53,963.

Specification for Design.

Patented Oct. 14, 1919.

Application filed March 20, 1919. Serial No. 283,933. Term of patent 7 years.

To all whom it may concern:

Be it known that I, JOHN C. FLYNN, a citizen of the United States, residing at New York, in the county of New York, State of New York, have invented a new, original, and ornamental Design for Cabinet-Desks, of which the following is a specification, reference being had to the accompanying drawing, forming part thereof.

The figure is a perspective view, showing my new design.

I claim:

The ornamental design for a cabinet desk, as shown.

JOHN C. FLYNN.
